United States Patent

Des. 242,246
Patented Nov. 9, 1976

242,246

FOUNTAIN PEN

John Nicholas Butler and Stephen Peter Bartlett, London,
England, assignors to Alfred Dunhill Limited, London,
England

Filed Sept. 9, 1974, Ser. No. 504,660

Term of patent 14 years

Int. Cl. D19—06

U.S. CL. D19—49

FIG. 1 is a front elevational view of a fountain pen showing our new design with the cap separated from the body portion;

FIG. 2 is a left side elevational view thereof;

FIG. 3 is a rear elevational view thereof;

FIG. 4 is a top plan view of the cap of the fountain pen;

FIG. 5 is a top plan view of the body of the fountain pen;

FIG. 6 is a bottom plan view of the cap of the fountain pen;

FIG. 7 is a bottom plan view of the body of the fountain pen;

FIG. 8 is an enlarged scale cross-sectional view taken along line 8—8 of FIG. 1; and

FIG. 9 is a left side elevational view of the fountain pen showing the cap and body assembled together.

We claim:

The ornamental design for a fountain pen, as shown and described.
